WITNESS:

E. R. Rupprecht.

J. A. Marley
INVENTOR.

BY
Victor J. Evans
ATTORNEY.

UNITED STATES PATENT OFFICE.

JESSE ARTHUR MARLEY, OF NORTH CHICAGO, ILLINOIS.

GAS-LINE LOCK FOR AUTOMOBILES.

1,359,411.

Specification of Letters Patent. Patented Nov. 16, 1920.

Application filed December 8, 1919. Serial No. 343,153.

To all whom it may concern:

Be it known that I, JESSE A. MARLEY, residing at North Chicago, in the county of Lake and State of Illinois, have invented 5 new and useful Improvements in Gas-Line Locks for Automobiles, of which the following is a specification.

This invention relates to attachments for motor vehicles, particularly to locks therefor, and has for its object the provision of a valve interposed in the gas line between the tank and carburetor, the valve being provided with means whereby it may be locked in closed position whereby to prevent 15 theft of an automobile.

An important and more specific object is the provision of a device of this character in which the valve is of the gate type and screw operated whereby it may be moved to 20 open or closed position, the actuating member being operable by means of a key.

Another object is the provision of a device of this character which will be simple and inexpensive in manufacture and installation, which may be applied at any desired point between the gas tank and carburetor, which will be efficient and positive in action, durable in service, and a general improvement in the art.

With the above and other objects and advantages in view, the invention consists in the details of construction to be hereinafter more fully described and claimed, and illustrated in the accompanying drawing in 35 which—

Figure 1 is a longitudinal sectional view through part of my device,

Fig. 2 is a longitudinal, sectional view taken on a plane parallel to Fig. 1, and

Fig. 3 is a longitudinal sectional view on a plane at right angles to that of Fig. 1.

Referring more particularly to the drawing, the letter A designates a portion of the gas line leading from the supply tank to 45 the carburetor, not shown, of an automobile.

In carrying out my invention I provide a valve casing 10 which is interposed and suitably connected within the gas line A 50 and which is provided centrally with a valve seat 11. Movable within the casing 10 and adapted to engage and close the seat 11, is a gate member 12 formed as a disk which is mounted for slidable movement 55 near and within which is threaded one end 13 of an operating stem 14. Connected in

any suitable manner, as by means of screw threads, with the valve casing 10 is a guide member 15 through which the stem 14 operates and upon the upper end of which is secured, as by threading, the cylinder barrel 16 of a lock structure. Rotatable within the barrel 16 is the lock cylinder 17 having the usual key slot 18. This lock mechanism is of course provided with the usual wards. 60 The upper end of the stem 14 extends into the cylinder 17 and is formed for engagement by a suitable key 19 insertible within the slot 18 and adapted to rotate the cylinder 17. 70

The device being in position, in order to close and lock the gas line, it is merely necessary that the operator insert the key 19 within the slot 18 and give it several complete rotations in the proper direction, 75 whereupon the consequent rotation of the stem 14 will cause movement of the gate valve 12 into engagement with its seat, cutting off communication with the pipe line A. It is of course obvious that when the 80 valve is closed the automobile thus equipped cannot be stolen as there is no means for supplying gasolene, or whatever other fuel is used, to the carburetor. When it is desired to reestablish communication it is 85 merely necessary that the operator reinsert the key and rotate the cylinder in the opposite direction whereupon the valve 12 will be disengaged from its seat.

In order to provide protection for the device I make use of a hood 20 formed as a shell threaded or otherwise secured upon the valve casing 10 and inclosing the upper portion thereof, the member 15 and the cylinder barrel 16. 90

While I have shown and described the preferred embodiment of my invention, it is of course to be understood that I reserve the right to make such changes in the form, construction, and arrangement of parts as 100 will not depart from the spirit of the invention or the scope of the subjoined claim.

Having thus described my invention, I claim:—

A device of the character described comprising a valve casing interposed in the gas line pipe of an automobile and provided with a valve seat, a valve slidable within said casing and adapted to close said seat, said valve member being formed as a disk 105 having a threaded opening, a guide sleeve member threaded into said casing, a stem 110

2
rotatably disposed within said guide member and threaded at one end for engagement within the threaded opening in said valve member, a lock structure including a cylinder barrel casing mounted upon said guide member and having a disk-like head, a cylinder barrel rotatable within said barrel casing and provided with a key receiving slot, the other end of said stem extend-

ing into said cylinder barrel, a key insertible in said slot to rotate said barrel and thereby to effect rotation of the stem to seat or unseat said valve, and an enlarged portion formed on said casing, and a shell threaded onto said enlarged portion and engaging said head.

In testimony whereof I affix my signature.
JESSE ARTHUR MARLEY.
